US00D948620S

(12) United States Design Patent (10) Patent No.: US D948,620 S
(45) Date of Patent: * Apr. 12, 2022

(54) GAMING MACHINE

(71) Applicant: ARISTOCRAT TECHNOLOGIES AUSTRALIA PTY LIMITED, North Ryde (AU)

(72) Inventors: Michael Berry, Nashville, TN (US); Timothy Francis Barbour, Nolensville, TN (US); Bruce Edward Urban, Las Vegas, NV (US); Daniel Harden, Palo Alto, CA (US); Hirotomi Teranishi, San Jose, CA (US); Jase Ruggles, Chicago, IL (US); Cheng-Fu Hsieh, Palo Alto, CA (US); Ariel David Turgel, San Francisco, CA (US)

(73) Assignee: ARISTOCRAT TECHNOLOGIES AUSTRALIA PTY LIMITED, North Ryde (AU)

() Term: 15 Years

(21) Appl. No.: 29/665,593

(22) Filed: Oct. 4, 2018

(51) LOC (13) Cl. 21-01

(52) U.S. Cl.

USPC D21/369

(57) CLAIM

We claim the ornamental design for a gaming machine, as shown and described.

DESCRIPTION

FIG. 1 is a front perspective view of a gaming machine showing our new design;

FIG. 2 is a front view of the gaming machine shown in FIG. 1;

FIG. 3 is a right side view of the gaming machine shown in FIG. 1;

FIG. 4 is a left side view of the gaming machine shown in FIG. 1;

FIG. 5 is a top view of the gaming machine shown in FIG. 1; and,

FIG. 6 is a bottom view of the gaming machine shown in FIG. 1.

In these drawings, broken lines illustrate unclaimed environmental features and form no part of the claimed design.

1 Claim, 4 Drawing Sheets
